(57) **CLAIM**

The ornamental design for a vehicle wheel, as shown and described.

DESCRIPTION

FIG. 1 is a front elevational view of a vehicle wheel showing our new design; and,

FIG. 2 is a side perspective view of a front face thereof. Any broken lines represent an internal boundary of the design; the line itself and the area within form no part of the claim.

1 Claim, 2 Drawing Sheets Fig. 1
